UNITED STATES PATENT OFFICE.

VERNON F. KING, OF DAYTON, OHIO, ASSIGNOR TO THE NATIONAL CASH REGISTER COMPANY, OF DAYTON, OHIO, A CORPORATION OF OHIO, (INCORPORATED IN 1906.)

DESIGN FOR A CASING OR CABINET FOR SWITCHBOARDS FOR TELEPHONE SYSTEMS.

48,977.

Specification for Design.

Patented May 2, 1916.

Application filed December 17, 1914. Serial No. 877,816. Term of patent 3½ years.

To all whom it may concern:

Be it known that I, VERNON F. KING, a citizen of the United States, residing at Dayton, in the county of Montgomery and State of Ohio, have invented a new, original, and ornamental Design for Casings or Cabinets for Switchboards for Telephone Systems.

The accompanying drawing, forming a part of this specification, is a three-quarters front perspective from the left of the casings or cabinets for switchboards for tele-

phone systems having the design of the present invention.

What is claimed is:

The ornamental design for a casing or cabinet for switchboards for telephone systems as shown.

In testimony whereof I affix my signature in the presence of two witnesses.

VERNON F. KING.
